The ornamental design for a liquid atomizer, as shown and described.

DESCRIPTION

FIG. 1 is a perspective view of the liquid atomizer showing our new design.

FIG. 2 is a front view of the liquid atomizer shown in FIG. 1.

FIG. 3 is a rear view of the liquid atomizer shown in FIG. 1.

FIG. 4 is a left view of the liquid atomizer shown in FIG. 1.

FIG. 5 is a right view of the liquid atomizer shown in FIG. 1.

FIG. 6 is a top view of the liquid atomizer shown in FIG. 1; and,

FIG. 7 is a bottom view of the liquid atomizer shown in FIG. 1.

The broken lines in the drawings depict portions of the liquid atomizer that form no part of the claimed design.
